UNITED STATES PATENT OFFICE.

JOHN W. BEARD AND ALEXANDER H. SPEARS, OF MCCOOL, MISSISSIPPI.

PLOW.

SPECIFICATION forming part of Letters Patent No. 425,287, dated April 8, 1890.

Application filed August 9, 1889. Serial No. 320,321. (No model.)

To all whom it may concern:

Be it known that we, JOHN WILLIAM BEARD and ALEXANDER HAMILTON SPEARS, citizens of the United States, residing at McCool, in the 5 county of Attala and State of Mississippi, have invented certain new and useful Improvements in Plows; and we do declare the following to be a full, clear, and exact description of the invention, such as will enable others 10 skilled in the art to which it appertains to make and use the same.

This invention has relation to improvements 15 in seed-planters, and the novelty will be fully understood from the following description and claim, when taken in connection with the annexed drawings, in which—

Figure 1 is a perspective view of our improved planter. Fig. 2 is a plan view of the same; and Fig. 3 is a side elevation, partly 20 section, of the rear portion of the machine.

Referring by letter to the said drawings, E indicates a central longitudinal beam, which constitutes the main portion of the main 25 frame.

D D are lateral beams secured to the opposite outer sides of the central beam E, and between these lateral beams we secure a hopper A, having its spout H passing through the central beam.

C indicates handles, which may be of any ordinary construction, secured at their forward ends to the central beam E, and B B are grass-rods, bowed as shown, with their forward ends secured to the central beam in advance 30 of the hopper and their opposite ends secured to the handles.

F is a furrow-opener properly braced to the central beam of the main frame in front of the discharge-spout of the hopper, and G G 35 are covering-shovels arranged in rear of the hopper and secured, respectively, to the outer beams D.

R indicates a reciprocating seed-slide, which is provided with a dropping-aperture R and 40 arranged beneath the central beam E and adapted to move across the throat of the hopper. This reciprocating slide has secured to one end a spring N, which has its opposite end secured to a depending arm a, secured to the central beam E, so as to hold the slide 45 normally in a closed position within the hop-

per. This slide has its rear end provided with an arm O, rising vertically in rear of the main frame, for a purpose which will be presently explained.

55

L indicates bracket-arms secured at their forward ends to the central beam of the main frame, so as to furnish in their opposite ends bearings for the operating-wheel M. This wheel M is provided with an annular extension b on one side, as better shown in Fig. 2 of the drawings. The wheel is provided adjacent to its periphery on the side bearing the annular extension with a series of slides P, which are adapted to be adjusted radially. 60 These slides carry pins d, which are designed in the revolution of the wheel to strike the arm O on the seed-slide and drive it forward. By having these plates carrying the pins adjustable in respect to the periphery of the 65 wheel it is obvious that the stroke upon the arm of the slide may be varied, thereby adapting the machine for the planting of various kinds of grain.

Q indicates a scraper or coverer, which may 70 consist of a board of sufficient length. This board is secured to the main frame and the lateral beams thereof by yielding arms e.

Z indicates a rotary agitator suitably journaled within the hopper, and has its shaft 75 provided with a crank-arm, the wheel M having also a shaft provided with a crank-arm.

K indicates a pitman connecting the crank-arm on the shaft of the wheel M with the shaft or crank-arm of the agitator.

85

The central beam is provided at its forward end with a clevis for the attachment of the draft.

From the construction illustrated it will be seen that when it is not desirable to use the 90 machine as a planter the hopper may be removed from the frame, together with the lateral beams and operating-wheel, when a convenient plow may be had.

Having described our invention, what we 95 claim is—

The improved seed-planter described, consisting, essentially, of the central beam, the lateral beams secured thereto, the furrow-opener secured to the central beam, covering-shovels secured to the lateral beams, the hopper seated in the central beam and between 100

the lateral beams, the operating-wheel journaled in brackets secured to the central beam, the adjustable pins in the wheel, the spring-backed reciprocating seed-slide having the 5 arm O, to be engaged by the pins of the wheel, the scraper or coverer Q, secured to the frame by yielding arms, the handles secured to the central beam, and the grass-bars having one end secured to the central beam and their op-

posite ends secured to the handles, substantially as specified.

In testimony whereof we affix our signatures in presence of two witnesses.

JOHN W. BEARD.
A. H. SPEARS.
